(57) **CLAIM**

The ornamental design for a faucet valve body, as shown and described.

DESCRIPTION

FIG. 1 is a perspective view of a faucet valve body showing our new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is top perspective view illustrating the faucet valve body in one position within a faucet shown in broken lines; and,

FIG. 10 is another top perspective view illustrating the faucet valve body in another position within a faucet shown in broken lines.

The broken lines within the faucet valve body shown in broken lines are for the purpose of illustrating portions of the faucet valve body and form no part of the claimed design. The faucet shown in broken lines in FIGS. 9 and 10 are for the purpose of illustrating environment and form no part of the claimed design.
